Joseph Turner Utica, N.Y.

Seth's Patent

X9642

The volume referred to in the Seth's Patent and making part of the same containing a description in the words of the said Joseph Turner of his improvement in the double Suction-pump for raising Water.

I, John Hall, present declare and believe that I, Joseph Turner, of Flora County of Cumberland and state of Maine, have invented a new and useful improvement in a machine, for raising Water and other purposes called the double lever pump, and that the following is a full and exact description of the construction and operation of said machine as invented or improved by me. The ribs of this machine are ten feet four inches long the sides twelve and three inches wide there are also two cross ribs of the same size. Of the long cross-rib framed arms, by means of tenons and mortises, some inches from the lower end shoulder each side of the centre of the long ribs so as to form a thick long square, twenty three inches. There are four posts, three on each long rib, having the tenons inserted in each corner of the frame, at the extremity of the side as to stand perpendicular as in letter A doth appear. Above these posts and with in the sides of the top there are fitted straight iron shafts, with three yokes in compass to bear the shaft one inch and a quarter square and project on each side through and thin them square down, making what is called the long arm of the machine being thirteen inches from the top of the shaft to the end and is graduated to three fourths of an inch square as in letter B doth appear. On each of these shafts and in the centre between posts there is inserted vertically a piece of iron twelve inches long from the outside of the shaft to the end which is three fourths of an inch square, making what is called the short arm, as in letter C doth appear in the same side of the machine and eight inches down the

so to there is fitted a bar long enough of the machine and secured at each end of the bar so as to be immovable to the bar of this bar there is a metal shuttle eight inches long and one and a half inches wide through which a two-hole foot long one inch and a half, square iron is fastened by an iron pin through the center of the shuttle and six inches from the lower end of the iron as in letter D) doth appear. At the top of this iron is fitted a iron frame bar six feet long and one inch in diameter by which the iron is retained. The iron is put proper straight and the long arm pointing directly down. Making the distance back way from the end of the bar to the end of the long arm twelve inches then there is a metal shuttle in the end of the bar and in the end of each of the long arms so as to admit two iron rods one inch wide and one three eighths of an inch thick so put together in the iron to form a joint in an iron pin the other end are fitted in each way in the end of the long arm with iron pins as in letter E) doth appear. This if used to raise material then fitted on the top of a pump rod or piston made fast to the end of the short arm and is put in motion by taking hold of the rod which is made fast to the top of the bar and then giving the arm the motion generally used in washing. This frame may be fitted on the pump rod as usual set at any distance whatever by lengthening or shortening the frame as the case may require and turning the short arms as desired.

That I claim as my invention and not previously known in the above described machine is the purchase obtained by the double lever and its application to pumping engines &c &c.
